(57) **CLAIM**

The ornamental design for a palm leverage handheld body strengthening apparatus handle, as shown and described.

DESCRIPTION

FIG. 1 is perspective view of a palm leverage handheld body strengthening apparatus handle showing my new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines in FIGS. 1-5 and FIG. 7 showing extended rods and rod connector are included for the purpose of illustrating environmental structure and forms no part of the claimed design.

1 Claim, 7 Drawing Sheets
